UNITED STATES PATENT OFFICE.

PAUL E. SCHLEICHER, OF CHICAGO, ILLINOIS, ASSIGNOR TO SCHLEICHER, INC., OF CHICAGO, ILLINOIS, A CORPORATION OF ILLINOIS.

DESIGN FOR A RADIATOR COVER.

Application filed May 16, 1925. Serial No. 13,467. Term of patent 14 years.

To all whom it may concern:

Be it known that I, PAUL E. SCHLEICHER, a citizen of the United States, and a resident of the city of Chicago, in the county of Cook and State of Illinois, have invented a new, original, and ornamental Design for a Radiator Cover or Similar Article, of which the following is a specification, reference being had to the accompanying drawings, forming a part thereof.

On the drawings:

The figure is a perspective view of the radiator cover involving the design of this invention.

I claim:

The ornamental design for a radiator cover or similar article as shown.

PAUL E. SCHLEICHER.
